UNITED STATES PATENT OFFICE.

CHARLES O. PEARSON, OF BROOKLYN, NEW YORK.

ELECTRIC WATER-HEATER.

1,187,924.

Specification of Letters Patent. Patented June 20, 1916.

Application filed May 26, 1915. Serial No. 30,497.

To all whom it may concern:

Be it known that I, CHARLES O. PEARSON, a citizen of the United States of America, and a resident of Brooklyn, Kings county, and State of New York, have invented certain new and useful Improvements in Electric Water-Heaters, of which the following is a specification, reference being had to the accompanying drawings, forming a part thereof.

My invention relates to electric heating apparatus and particularly to such as are adapted to receive water at a low temperature and to deliver the same continuously at either its normal temperature or at a relatively high temperature, the flow of water and the control of electric energy being dependent upon a single shut-off valve.

One object of my invention is to provide a simple and compact device of the aforesaid character that shall comprise a quick-acting circuit switching device operatively connected to a shut-off valve, a tortuous passage in an insulating body through which the water is conducted, and electric heating means disposed directly in the fluid passage.

It has been my aim to provide a compact water heater, capable of heating a relatively large quantity of water continuously and arranged so that practically all of the heat generated in the electric heating element of the device is taken up by the water; in other words, a device of a relatively large capacity and high efficiency.

Other objects and advantages of my invention will be set forth hereinafter and in order that my invention may be thoroughly understood, I will now proceed to describe the same in the following specification and then point out the novel features thereof in appended claims.

Referring to the drawings: Figure 1 is a sectional elevation, through the valve stem, of an electric water heater arranged and constructed in accordance with my invention. Fig. 2 is a similar view of the lower part of the heater, the section being taken through the outlet on the line 2-2 of Fig. 1. Fig. 3 is a sectional plan view on the line 3-3 of Fig. 1. Figs. 4, 5, 6, 8 and 9 are sectional plan views taken respectively on the lines 4-4, 5-5, 6-6, 8-8 and 9-9 of Fig. 1. Fig. 7 is a partial elevation which is also in section and is taken on the line 7-7 of Fig. 4.)

The structure illustrated comprises a body 10 substantially cylindrical in form and made of cast metal. Depending from the body is a cylindrical box or casing 11 which is lined and capped with insulation and contains a quick break electric switch and means for operating the same.

The body 10 has an upwardly extending flange 12 which is internally threaded and supports a cylindrical metal shell 13 having a cap 14 screwed onto its upper end. Within the shell 13 are a plurality of cylindrical blocks 15, 16, 17, 18 which are preferably formed of porcelain or some other hard molded insulating material and are cemented and fired, or otherwise sealed together to virtually constitute a single block of electric and heat insulating material. As herein-after explained the blocks are constructed to form grooves which provide a continuous tortuous passage through which water flows and in which is disposed the heating element of the device.

The cylindrical body 10 is hollow being subdivided into two chambers 19 and 20 and a recess 21, and is closed at the top. A tubular projection 22 extends downwardly from the body and constitutes an inlet with which any suitable pipe connection may be made, which inlet is adapted to be shut off or opened into either the chamber 19 or the chamber 20.

A relatively small passage 23 connects the chambers 19 and 20 which are opposite and in alignment with each other, as shown in Fig. 2. Thus shoulders 24 are formed adjacent to the opening in the passage 23 in each of the chambers. Against these shoulders in the respective chambers, valves 25 and 26, which are similar to each other in structure, are pressed by springs 27.

The recess 21 extends substantially at right angles to the common center line of the chambers 19 and 20, and it has a hollow extension 28 which is in communication with the passage 23. A controlling or actuating block 29 is rotatively mounted in the extension 28 of the recess 21 and has an eccentric finger 30 which extends into the passage 23 as clearly shown in Figs. 1 and 2.

As hereinafter explained, the actuating block 29 has an additional function to perform and is provided with beveled gear teeth as shown at 31, for the purpose of actuating a vertical shaft 32. A shaft 33

extends outwardly through a suitable plug 34 in the opening of the chamber and a stuffing box 35.

The handle lever 36 is secured to the outer end of the shaft 33 so that it may be turned conveniently. The stuffing box is provided with a cap 37 and the shaft 33 has a collar 38 which fits into a recess 39 in the inner end of the plug 34, a spring 40 being interposed between the bottom of the recess and the collar and tending to force the shaft and the actuating block 29 inwardly. This structure is such as to seal the recess 21 from the passage 23 and the chambers 19 and 20, since the latter are fluid containing chambers while the recess 21 is only intended as a suitable means of support for the actuating parts of the fluid-control valves and electric circuit controlling switch.

When the shaft or post 33 is in one position, which is conveniently determined by setting the handle 36 to occupy a vertical position, the eccentric finger 30 is in a central position between the valves 25 and 26.

Under these conditions both valves are closed as shown in Fig. 2.

When the handle is turned in one direction, the eccentric moves to the right in Fig. 2 and opens the valve 26, thereby opening communication directly from the inlet passage 22 to the chamber 20, while if the handle is moved in the opposite direction the eccentric moves to the left in Fig. 2 and pushes back the valve 25, establishing communication from the inlet passage 22 to the chamber 19.

As hereinafter explained, a tortuous heating passage is connected at its inlet end to the chamber 19 and at its outlet end to the chamber 20 and accordingly liquid either flows through the passage or is discharged directly without flowing through the heating passage.

As above intimated, the chamber 20 communicates with the outlet which is designated by reference character 41 and which is screwed into the internally-threaded open end of the chamber.

As already pointed out, the valves 25 and 26 are similar to each other and it is only necessary to describe one of them in detail. For example, the valve 25 comprises a tubular clamping socket 42 which is internally-threaded to receive the shank 43 of a cooperating clamping member 44, the valve washer being hollow to permit the shank 43 to extend through it and being clamped between the members 42 and 44.

The valve is guided at one end by the clamping member 44 which is loosely fitted into the passage 23 and at the opposite end by a plug 45 which has a recess 46 to receive the tubular extension of the clamping member 42. This tubular member slides freely in the recess and the spring 27 is interposed

between the plug 45 and the shoulder 47 near the opposite end of the clamping member. The spring thus tends to close the valve as already explained.

The valve 26 is similar to the valve 25 except that at its outer end it is guided by a slotted bushing 48 which is set into a recess in the outlet 41, the spring in this instance being interposed between the bushing and the shoulder of the clamping member instead of between the plug and the shoulder of the clamping member as in the case of the valve 25.

The porcelain block 15 which is illustrated in detail in Fig. 4 has a hole 50 which extends through it and communicates through a groove 49^a with a hole 49 in the body 10. The hole opens into the chamber 19 which, as already explained, may be opened into the inlet passage 22 of the device. The block 15 is furthermore provided with a tortuous groove 51 which communicates at one end with the hole 50 and at its opposite end with a hole 52 in the block 16 above. This block has a tortuous groove 53 which opens at one end into the hole 52 and communicates at its opposite end with a hole 54 in the block 17 above. This block also has a tortuous groove 55 communicating with the hole 54 at one end and at its opposite end with a hole 56 in the block 18 above. The top block 18 has a tortuous groove 57 interposed between the hole 56 and a central hole 58. Each of the blocks 15, 16, and 17 is also provided with a similar hole marked with the same reference character 58, all of which co-operate to provide a vertical passage through which fluid may flow downwardly after passing through the successive tortuous grooves. The block 15 at the bottom is furthermore provided with a short groove 59 on its bottom surface which establishes communication from the hole 58 to a hole 60 opening into the outlet chamber 20.

As shown in Fig. 4, a pair of electric circuit terminal posts 61 and 62 extend upwardly from within the hollow body 10 into and through the block 15. The terminal 62, as clearly shown in Fig. 7, is provided with a sleeve 63 of insulating material having a recessed enlargement 64 at its lower end and at its opposite end a projection 65 which extends through a suitable hole 66 in the body and into a recess 67 in the block 15.

The terminal comprises a socket member 68 which is disposed in the recess 64 of the insulating sleeve and is secured to the bottom end of a stud 69 which forms the body of the terminal. This stud extends upwardly through a hole 70 in the block 15 and into a recess 71 in its top surface.

The terminal 61 is similar to the terminal 62 and is similarly mounted relative to the body 10 of the device but its shank instead of extending completely through the

block 15 extends only into a recess 72 in its lower surface corresponding to the recess 67.

The recess 71 has a small passage or slot establishing communication to the groove 51 5 and the recess 72 is similarly connected to the groove 59 in the bottom surface of the block 15.

The resistance element of the heater may be formed in any suitable way and as shown 10 in the drawings it comprises a wire of resistance material formed into a helix 73. One end of this helix is twisted around and soldered or otherwise securely fastened mechanically, as well as electrically connected 15 to the stud 69 of the terminal member 62. The helix extends through the grooves 51, 53, 55 and 57 and through the central hole 58, its opposite end being connected to the terminal 61 as clearly shown in Fig. 4. The 20 resistance element is thus disposed directly in the water passage but it obviously will not interfere with the flow of water there- through.

The switch box or casing 11 is lined with 25 insulation and closed by an insulating cap 74 as already explained. The tubular extension 22 of the body which constitutes the water inlet of the device, extends completely through the box and constitutes a support 30 on which a sleeve 75 is rotatively mounted. Secured to this sleeve and insulated from it are a pair of switch members 76 and 77 each having a pair of blades 78 and 79.

The switch blades are adapted to respec- 35 tively coöperate with stationary switch contacts 80 and 81. The arrangement of parts is such that when the sleeve 75 and its attached parts occupy the position shown in Fig. 5, which is accentuated by the engage- 40 ment of a pawl 82 with a notch 83, the circuits of the electric heater are interrupted on each side of the line in a well known manner, and when the sleeve is mounted to a position accentuated by the engagement 45 of another pawl 84 with a notch 85, the circuits are closed.

The pawls 82 and 84 are mounted to slide in stationary supports 86 and 87 and are pressed into engagement with a notched 50 flange 88 of the sleeve, by means of springs 89 and 90.

A spring 91 is coiled about and secured at an intermediate point to the sleeve 75 and its ends are arranged to engage a stationary 55 post 92 in such a way as to cause the sleeve to move rapidly from one of its accentuated positions to the other, thereby providing a quick make and break action of the switch. This is accomplished in the following manner: When the ring 93 is turned in a clockwise direction, Fig. 5, the spring 91 is tightened but the sleeve 75 which carries the switch blades does not move until a cam 99 60 extending from the upper part of ring 93, 65 as is shown in this Fig. 5, engages pawl 82

and pushes it back out of notch 83. Then the sleeve 75 has a quick movement until pawl 84 arrests it by moving into notch 85. At this point the switch blades 78-79 will be in engagement with the contacts 80-81. 70 On returning to the open position of the switch, the pawl 84 holds sleeve 75 until released by cam 99, and pawl 82 entering notch 83 arrests and holds the sleeve in the position shown with the switch open. 75

A ring 93 having a toothed gear segment 94 is mounted on the sleeve 75 and is secured thereto. It is adapted to mesh with a gear wheel 95 secured to the lower end of the shaft 32. A bevel gear 96 is secured to, 80 or forms a part of, the shaft 32 at its upper end and meshes with the bevel gear 31. The shaft 32 is mounted in a suitable bearing 97 and is obviously rotated to throw the switch into one position or the other as 85 the handle 36 is turned to open one or the other of the valves 25 and 26.

The arrangement of parts is such that when the valve is turned to connect the water inlet passage directly to the outlet 90 chamber 20, electric energy is not supplied to the heater, the switch being in its open position. With the handle thrown to its opposite position to open the valve 25 and establish a water passage from the inlet 95 through chamber 19, the tortuous passage in the blocks 15 to 18 inclusive, and finally out through the hole 58 and the chamber 20, the switch is closed.

Under the last-named conditions, the electric 100 energy is supplied to the resistance element which is disposed in the tortuous passage and the heat generated in the element is transferred directly to the water. This resistance is designed to raise the temperature of the water to the degree desired. Heat is supplied to the water during the time it flows through the passage and it is only necessary to open the valve and permit the water to flow through the passage for 110 a short time until a continuous flow of hot water is commenced.

The blocks 15, 16, 17 and 18 in addition to being cemented together, are preferably held together by rivets or bolts 100. 115

It is obvious that this apparatus may be used with other liquids than water, and that structural variations may be effected within the spirit and scope of my invention. I intend that only such limitations be imposed 120 as are indicated in the appended claims.

What I claim is:

1. An electric heater comprising an insulating body having a plurality of sections, grooves in the adjacent surfaces of the sections together forming a conduit and holes through the sections communicating with the grooves to constitute a continuous and tortuous passage through the insulating body, and an electric heater element dis- 125 130

- posed in the passage and arranged to permit the flow of fluid therethrough.
2. An electric heater comprising an insulating body having a plurality of sections, 5 grooves in the adjacent surfaces of the sections together forming a conduit and holes through the sections communicating with the grooves to constitute a continuous and tortuous passage through the insulating 10 body, and a helical resistance wire heater element disposed in the passage.
3. An electric heater comprising a plurality of cylindrical blocks of hard molded insulating material adapted to be assembled 15 bled end to end, the end surfaces of the blocks being provided with tortuous grooves and the blocks having holes through them to connect successively the grooves to form a single tortuous passage through the body, 20 means for uniting the blocks into a unitary body, and a heater element disposed in the passage and arranged to permit the flow of fluid to be heated therethrough.
4. An electric heater comprising a plurality of cylindrical blocks of hard molded insulating material adapted to be assembled 25 end to end, the end surfaces of the blocks being provided with tortuous grooves and the blocks having holes through them to connect successively the grooves to form a single tortuous passage through the body, means 30 for uniting the blocks into a unitary body, and a helical resistance wire heater element disposed in the passage.
- 35 5. An electric water heater comprising a metal body having a pair of opposite chambers, a passage joining the chambers, and an inlet opening into the passage, a pair of valves located in the respective chambers 40 and adapted to close the openings from the chambers into the passage; and a heater comprising an insulating body having a plurality of sections, grooves in the adjacent surfaces of the sections together forming a 45 conduit and holes through the sections communicating with the grooves to constitute a continuous and tortuous passage through the insulating body, and an electric heater element disposed in the passage and arranged 50 to permit the flow of fluid therethrough, said passage being interposed between the chambers.
6. An electric water heater comprising a metal body having a pair of opposite chambers, a passage joining the chambers, an 55 inlet opening into the passage, a pair of valves located in the respective chambers and adapted to close the openings from the

chambers into the passage, and a helical resistance wire heater element disposed in the 60 passage, said passage being interposed between the chambers.

7. An electric water heater comprising a metal body having a pair of opposite chambers, a passage joining the chambers, an inlet opening into the passage, a pair of valves located in the respective chambers and adapted to close the openings from the chambers into the passage, a helical resistance wire heater element disposed in the 70 passage, said passage being interposed between the chambers, an outlet secured to the body and communicating with one of said chambers, and a controller for opening one or the other of said valves. 75

8. An electric water heater comprising a metal body having a pair of opposite chambers, a passage joining the chambers, an inlet opening into the passage, a pair of valves located in the respective chambers and 80 adapted to close the openings from the chambers into the passage, a helical resistance wire heater element disposed in the passage, said passage being interposed between the chambers, an outlet secured to the body and communicating with one of said chambers, a recess in the body opening into the passage between the chambers, and a controller rotatively mounted in the recess and having an eccentric projection extending 85 into the passage and adapted to actuate the valves. 90

9. An electric water heater comprising a metal body having a pair of opposite chambers, a passage joining the chambers, an inlet opening into the passage, a pair of valves located in the respective chambers and 95 adapted to close the openings from the chambers into the passage, a helical resistance wire heater element disposed in the 100 passage, said passage being interposed between the chambers, an outlet secured to the body and communicating with one of said chambers, a recess in the body opening into the passage between the chambers, a controller rotatively mounted in the recess and having an eccentric projection extending 105 into the passage and adapted to actuate the valves, a switch for controlling the electric circuit of the heater, and an operative connection between the controller and the switch. 110

In witness whereof, I have hereunto set my hand this 18 day of May, 1915.

CHARLES O. PEARSON.
